SHAVING DEVICE

John B. Gormley, Boston, Mass.

Application July 1, 1936, Serial No. 88,376

10 Claims. (Cl. 30—43)

My invention relates to a shaving device for use in so-called "dry shaving."

The invention has among its objects the provision of a shaving device of this type which is of simplified construction and adapted better to operate upon the face of the user.

The invention will be best understood from the following description when read in the light of the accompanying drawing of one embodiment of the invention selected for illustrative purposes, the scope of which invention will be more particularly pointed out in the appended claims.

In the drawing:—

15 Fig. 1 is a side elevation of a shaving device constructed according to the invention;

Fig. 2 is a section on the line 2—2 of Fig. 1 on an enlarged scale;

20 Fig. 3 is a plan of the device according to Fig. 2;

Fig. 4 is a plan of the rotary shearing member and associated shaft; and

Fig. 5 is a side elevation according to Fig. 4.

The shaving device illustrated in the drawing 25 comprises a cup-shaped casing 1 of thin sheet metal, the base of which is formed with a marginal bead adjacent its periphery. As shown, this bead has a flat outer face 3 in a plane normal to the axis of the casing and has opposite flaring side walls 5 and 7, so that the bead radially thereof in cross-section has a V-shaped contour with the apex of the V cut away. In practice the casing may be approximately the size indicated by Fig. 1.

30 The bead above described is formed with a plurality of closely spaced parallel slots 9, these slots, as illustrated, intersecting the outer face 3 and opposite side walls 5 and 7 of the bead.

40 The slots in the inner wall 7 as shown extend to approximately the bottom wall 11 of the recess surrounded by the bead, and the slots in the outer wall 5 slightly intersect the adjacent end of the cylindrical wall of the casing. If desired, 45 slots in the side walls 7, other than those formed therein by the ends of the slots in the face 3, may be omitted.

45 The slotted bead above described forms a "comb", and the material of the bead between each pair of adjacent slots forms one element of a shearing couple. The other shearing element of the couple is positioned at the inner side of the bead, and is movable relative to the casing so that the hairs which enter the slots of the bead will 50 be sheared off. These shearing elements within

the bead preferably, but not necessarily, are rotary.

As illustrated, within the casing is a member comprising the disk 13 formed with a plurality of flat radial blades 15. As shown, the upper surfaces of the disk and blades are shaped to conform exactly to the inner side of the wall 11 of the casing and the face 3 and side walls 5 and 7 of the bead. By this construction, when the disk is rotated an edge of the upper surface of each blade cooperates with an edge of the portion of the bead between each pair of adjacent slots to form shearing couples. It will be noted that the blades 15, which extend radially of the bead, will for the most part intersect 15 the slots at an angle, and thereby facilitate the shearing operation, the action of the shearing couples so formed being closely like that of the usual shears having pivotally connected blades as in the ordinary scissors.

20 As illustrated, the casing 1 is mounted on a base formed by the casing 17 of an electric motor adapted to be held by the hand of the user. As shown, the casing of the motor has a reduced cylindrical end portion 19 and a shoulder 21, the 25 flexible cord 22 for energizing the motor entering the opposite end of the casing. The open end of the casing 1 is slid over this cylindrical end portion in abutting relation with the shoulder, and is detachably secured to the casing 17 by a 30 set screw 23 tapped into the wall of the portion 19 and extending through a suitable opening in the wall of the casing 1.

25 For rotating the blades 15 the disk 13 is shown as provided with an axially positioned square 35 hole 25 which receives the correspondingly shaped reduced end portion 27 of a cylindrical shaft 29. As best illustrated, the lower end of the shaft 29 is provided with a cylindrical bore 31 which 30 slidably receives the reduced end portion 33 of the rotary motor shaft 35. The portion 33 of the shaft 35, as illustrated, is provided with a pin 37 extending diametrically therethrough and having projecting end portions. These end portions are received in the slots 39 formed in the 40 walls of the bore 31 at the lower end of the shaft 29, so that the shaft 29 is forced to rotate with the shaft 35 in the assembled device. As 45 shown, the shaft 35 is provided with a collar 41 which serves as an abutment for the lower end of a light compression spring 43, the upper end of the spring abutting against the under side of the disk 13. It will be noted by this construction that in effect a longitudinally extensible shaft is 50 provided for rotating the disk 13, and that this 55

construction causes the spring 43 to hold the upper surfaces of the blades 15 in yielding contact with the under surfaces of the bead on the end of the casing 1.

5 For lubricating the device the upper end of the shaft 29 is shown as provided with a small cup-shaped recess 45 adapted to receive grease as, for example, petroleum jelly. Communicating with this recess are grooves 47 which extend radially 10 across the upper surfaces of the disk 13 and blades 15, so that the surfaces of the disk and blades which contact with the under surfaces of the bead and central portion 11 of the end of the casing 1 will be lubricated.

15 It has been found that the shaving device above described will remove the hairs much more rapidly than shaving devices of the "dry shaving" type heretofore proposed, thus enabling the device to be moved more rapidly over the face and to 20 complete the shaving operation in less time than with prior devices. Further, with prior devices of this type it is necessary, particularly when a "close shave" is desired, to draw the skin upward toward the scalp in advance of the comb so as to 25 make the hairs project at right angles to the skin and enter the interstices of the comb. This is unnecessary with the shaving device above described for the reason that when the bead is pressed against the face the skin tends to be 30 pushed up into the recess surrounded by the inner side 7 of the bead, which suitably tensions the skin, particularly when the device is moved in an upward direction along the face or neck, and causes the hairs to stand out from the skin and 35 enter the comb. Still further, the rounded bead permits the ready removal of hairs from portions of the face ordinarily difficult to shave as, for example, the upper lip adjacent the nose, the chin adjacent the lower lip, and the sides of the 40 face about the ears. This is due to the fact that the bead being rounded may be tilted to present only a small portion of the outer face 5 of the bead to such portions to be shaved.

45 It will be understood that within the scope of the appended claims wide deviations may be made from the form of the invention described without departing from the spirit of the invention.

I claim:

50 1. A shaving device having, in combination, a skin contacting member formed to present a thin walled annular part having a face portion and an outer side wall inclined outwardly of said face portion, said face portion and wall provided with 55 narrow closely spaced slots to form a comb and a plurality of hair shearing elements, and a movable member within said skin contacting member contacting with the slotted portion thereof to provide a shearing element cooperating with the 60 first mentioned shearing elements.

65 2. A shaving device having, in combination, a skin contacting member formed to present a thin walled annular part having a face portion and an outer side wall inclined outwardly of said face portion, said face portion and wall provided with 70 narrow closely spaced slots to form a comb and a plurality of hair shearing elements, and a rotary member within said skin contacting member contacting with the slotted portion thereof to provide a shearing element cooperating with the first mentioned shearing elements.

75 3. A shaving device having, in combination, means forming a thin walled annular skin contacting bead having concentric oppositely diverging side walls, said walls and the face portion of

5 said bead being formed with narrow closely spaced parallel slots to form a comb and a plurality of hair shearing elements, and a movable member in said bead contacting with the slotted portion thereof presenting a plurality of shearing elements 10 cooperating with the first mentioned shearing elements.

4. A shaving device having, in combination, means forming a thin walled annular skin contacting bead having concentric oppositely diverging side walls, said walls and the face portion of 15 said bead being formed with narrow closely spaced parallel slots to form a comb and a plurality of hair shearing elements, and a rotary member in said bead contacting with the slotted portion thereof presenting a plurality of shearing elements 20 cooperating with the first mentioned shearing elements.

5. A shaving device having, in combination, a skin contacting member formed to present a thin 25 walled annular bead having an outer annular flat face confined to a single plane and annular relatively flaring side walls, said bead being formed with narrow closely spaced parallel slots intersecting the face and at least the outer side 30 wall of said bead to form on said face and side wall of said bead a comb and a plurality of hair shearing elements, and a movable member in said bead presenting a plurality of shearing elements 35 in contact with the slotted portion of said bead and cooperating with the first mentioned shearing elements.

6. A shaving device having, in combination, a skin contacting member formed to present a thin 40 walled annular bead having an outer annular flat face confined to a single plane and annular relatively flaring side walls, said bead being formed with narrow closely spaced parallel slots intersecting the face and at least the outer side wall of 45 said bead to form on said face and side wall of said bead a comb and a plurality of hair shearing elements, and a rotary member in said bead presenting a plurality of shearing elements in contact with the slotted portion of said bead and cooperating with the first mentioned shearing elements.

7. A shaving device having, in combination, a skin contacting member formed to present a thin walled annular bead having an annular face confined to a single plane and annular oppositely inclined side walls, so that the bead in cross-section radially thereof presents a V-shaped contour with the apex of the V cut away, said bead being formed with a plurality of closely spaced parallel slots intersecting the face and side walls of said bead to form on said face and side walls a comb and a plurality of hair shearing elements, and a movable member in said bead presenting a plurality of shearing elements cooperating with the first mentioned shearing elements.

8. A shaving device having, in combination, a skin contacting member formed to present a thin walled annular bead having an annular face confined to a single plane and annular oppositely inclined side walls, so that the bead in cross-section radially thereof presents a V-shaped contour with the apex of the V cut away, said bead being formed with a plurality of closely spaced parallel slots intersecting the face and side walls of said bead to form on said face and side walls a comb 70 and a plurality of hair shearing elements, and a rotary member in said bead presenting a plurality of shearing elements cooperating with the first mentioned shearing elements.

9. A shaving device comprising, in combina- 75

tion, a base part, a casing member carried by said part, said casing member having a thin walled annular skin contacting part having a face portion and an outer side wall inclined outwardly of said face portion, said face portion and wall having a plurality of narrow closely spaced parallel slots to form a comb and a plurality of hair shearing elements, a rotary member in said casing member having a plurality of shearing elements in contact with the slotted portion of said skin contacting part, spring means within said casing member for holding said shearing elements of said rotary member yieldingly in contact with said shearing elements of said skin contacting part, and a rotary shaft carried by said base part coaxial with said skin contacting part for rotating said rotary member.

10. A shaving device comprising, in combination, a base part, a cylindrical casing carried by

said part, the end of said casing opposite said part being formed to present a thin walled annular skin contacting bead having an annular flat face and annular oppositely inclined side walls, so that said bead in cross-section radially thereof 5 presents a V-shaped contour with the apex of the V cut away, said bead having narrow closely spaced parallel slots intersecting the face and at least the outer side wall of said bead to form a comb and a plurality of hair shearing elements, 10 a rotary member in said casing having shearing blades contacting with the slotted portion of said bead, a longitudinally extensible rotary shaft means carried by said base part coaxial with said bead and carrying said rotary member, and 15 spring means for urging extension of said shaft means for holding said shearing elements of said rotary member in contact with said bead.
